UNITED STATES PATENT OFFICE

JOHN BARNES, OF ROCKFORD, ILLINOIS.

IMPROVEMENT IN HARVESTER-RAKES.

Specification forming part of Letters Patent No. **157,672**, dated December 15, 1874; application filed October 22, 1874.

To all whom it may concern:

Be it known that I, JOHN BARNES, of Rockford, in the county of Winnebago and State of Illinois, have invented certain new and useful Improvements in Harvester-Rakes, of which the following is a specification:

My invention relates to that class of combined reel and rakes shown in Letters Patent of the United States granted to me, and respectively numbered and dated No. 85,723 of January 12, 1869, and No. 114,094 of April 21, 1871.

The subject-matter claimed is hereinafter specified.

The accompanying drawings show so much of the raking apparatus as is necessary to illustrate my invention.

Figure 1 is a plan view; Fig. 2, a view in perspective of the rake-arm detached; Fig. 3, a vertical central section through the guide-post; and Fig. 4, a detail view of the gearing which controls the rake.

The crown-wheel A, upon which the rake and reel arms are mounted, revolves around a guide-post, B, fixed upon the frame, having its upper end bent eccentrically to the axis of rotation of the crown-wheel. The reel-arms C are suspended from the upper part of this guide-post by links c. The rake-arm D is pivoted upon the crown-wheel in such manner that it extends obliquely backward of a radial line drawn through the crown-wheel. A bracket, E, is pivoted upon the rake-arm in such manner as to permit it to oscillate or swing slightly in a horizontal plane upon its pivot e. A link, E', connects the outer end of this bracket with the guide-post. A pitman, F, is pivoted at one end to the bracket, while its other end is swiveled to a crank, f, of a shaft, F', mounted in suitable bearings in the crown-wheel, carrying on its lower end, beneath the crown-wheel, a pinion, G, which engages at suitable intervals with the teeth h of a rack fixed upon the frame. The shaft F' carries a guide-plate, g, which is made concave to fit the perimeter of the ring or track H, on which the teeth h are fixed, the effect of which is to hold the shaft, and prevent it from turning on its own

axis at certain intervals, without, however, interrupting its rotation with the crown-wheel.

In Fig. 4 the spur-pinion G is shown as engaged with the rack, and the crank-shaft of course is rotating on its own axis as well as revolving with the crown-wheel. As the pinion G escapes from the fixed rack h, the guide-plate g interlocks with the ring H, and prevents the rotation of the crank-shaft, until its pinion G is about to re-engage with the rack h, when the lug on the guide-plate enters a recess, i, and brings the pinion and rack into gear again.

This is, in fact, the well-known Smith stock movement; and it is obvious that the same movements may be obtained in other well-known equivalent ways.

The gearing which actuates the crank-shaft F' may, if preferred, be arranged above instead of below the crown-wheel.

I have shown my improved rake as adapted to a one-wheel, rigid-bar machine; but, obviously, it may be applied to any of the approved harvesters of the present day.

The relative arrangement of my improved mechanism is such that the crank-shaft F' is prevented from rotating from the time the rake is elevated, and while it is moving forward over the driving-wheel, and the rake is consequently held up positively; but when the proper time comes for the rake to descend into the standing grain the crank-shaft rotates, allows the rake to drop squarely into the standing grain, holds it positively down upon the platform while the gavel is being swept therefrom, allows the swinging movement of the bracket and link, and assists the rake to rise faster than it otherwise would do by the operation of the guide-post and link alone.

I do not, broadly, claim herein the oblique arrangement of the rake-shaft or the swinging bracket, as they constitute the subject-matter of separate applications for Letters Patent filed by me simultaneously herewith.

What I do claim as my invention, and desire to secure by Letters Patent, is—

The combination of the rake-post, revolv-

ing crown-wheel, the rake-arm pivoted thereon, and linked to the guide-post by a swinging bracket and link, constituting an extensible connection, the pitman connecting such swinging bracket with a crank-shaft mounted upon the driving-wheel, and intermittently operated by stop-motion gearing, substantially such as described, whereby the rake-

arm is positively controlled in its rotation, substantially as hereinbefore set forth.

In testimony whereof I have hereunto subscribed my name.

JOHN BARNES.
